UNITED STATES PATENT OFFICE.

ALFRED G. F. KUROWSKI, OF BROOKLYN, NEW YORK, ASSIGNOR TO UNDERWOOD TYPE-WRITER COMPANY, OF NEW YORK, N. Y., A CORPORATION OF DELAWARE.

TYPEWRITING MACHINE.

Application filed August 4, 1922. Serial No. 579,560.

To all whom it may concern:

Be it known that I, ALFRED G. F. KUROWSKI, a citizen of the United States, residing in Brooklyn Borough, in the county of 5 Kings, city and State of New York, have invented certain new and useful Improvements in Typewriting Machines, of which the following is a specification.

The present invention relates to sound-deadening casings for typewriting machines; that is to say, to casings in which the machine may be operated with a minimum of noise. The invention also relates to certain features of the machine itself for 10 enhancing the deadening of sound when the machine is within the casing, and for the more successful operation of the same within the casing.

An object of the invention is provision of 15 simple and novel means whereby (more particularly for access to the types) the casing may be opened in the immediate vicinity of the keyboard.

A feature of the invention is the provision 20 of cover-opening means which may, except for a projecting finger or palm piece, be wholly contained within, and thus protected by, the casing; and which, therefore, besides offering a neat-appearing casing, offers a 25 casing in which the walls thereof require a minimum of openings; thus simplifying its manufacture, and reducing to a minimum the joints to be closed against emission of sound.

The character of casing to which the invention, more particularly as to certain features thereof, has reference, is a casing having 30 an opening in the front wall thereof, of sufficient size to permit passage therethrough 35 of the keyboard of the machine when the machine is inserted into the casing through the top of the latter. In such a casing the front plate of the typewriting machine serves (when the machine is in place) as a 40 closure for the opening in the front wall of the casing, above the keyboard extension of the machine. In front-strike typewriting machines in which the type-bars swing upward and rearward to the platen, and in 45 normal position form a segmental type-basket, the front plate of the machine has a segmental opening therein for access to the type-bars for cleaning. In order, therefore, 50 that the front plate of such a machine may 55 close the opening in the front wall of a cas-

ing of the character mentioned, a removable or movable, plate or door, to close the segmental opening in the front plate of the machine, has heretofore been provided. To permit of access for cleaning, such door 60 plates have been bodily removable from the interior of the casing when the casing is opened.

An object of the present invention is the provision of a sound-deadening door or 65 plate for the purposes mentioned, which door may be opened and closed by a simple movement, without otherwise opening the casing, and without bodily removal of the door.

A feature of the invention is a mounting 70 of the door on the front plate of the machine, permitting the door to be swung open on hinges by a finger-piece thereon; and in which provision is made for sealing, against 75 the emission of sound, the joint between the door and the front plate of the machine, when the door is closed.

A further feature of the invention is a 80 construction of the door itself, whereby it is rendered sound-proof by the incorporation of a sheet of sound-deadening material therein, and whereby the softer sound-deadening material is covered and protected from displacement or injury; the whole being 85 easily and securely assembled.

In casings of the character mentioned, the platen-carriage of the machine, with the line-space and other handles thereon, has movement in letter-feed and return directions. In order that the line-space lever may move with the carriage and nevertheless be operable from the outside of the casing, a slot is provided in the casing longitudinally of the front thereof; and, to seal this slot against emission of sound, its edges have 90 cushions which close it, except where the levers on the carriage project therethrough. These cushions necessarily exert a frictional pressure on the levers, and this pressure opposes the spring ordinarily employed for returning the line-space lever to normal position after each operation thereof. Owing to the resistance offered by the cushions, the return springs, as heretofore made and arranged for return of the line-space lever, have been injured or broken by wear, or have been insufficiently strong for the purpose.

An object of the invention is the provision 110

of a spring-return device for the line-space lever, and a mounting and setting of the spring thereof, which will act with certainty, and which will withstand long and 5 severe use without injury or breakage.

Other features and advantages will hereinafter appear.

In the accompanying drawings,

Figure 1 is a view, in cross-sectional side 10 elevation, of a casing equipped with the present invention; a typewriting machine being indicated in dotted lines within the casing.

Figure 2 is a view, in front elevation, of the casing of Figure 1 partly broken away; 15 the machine being shown in the casing, and the machine and the casing having thereon the devices of the present invention.

Figure 3 is a top plan view showing the line-space lever and connections thereof to 20 the platen-shaft.

Referring to the drawings, the casing is shown as comprising a body-portion 10 having a cover-portion 11 hinged at 12 thereto. The side walls of the body-portion are lined 25 with sound-deadening material, which is not shown except at 13, at the front thereof. The body-portion is also provided with a base-piece 14 of sound-deadening material, which may be secured thereto by screws. 30 The walls of the cover are also lined with sound-deadening material, not shown, except at 11^a in Figure 2. The cover is provided with a window 15, of glass or other transparent material, through which the 35 writing on the platen may be observed. The machine 16, indicated in dotted lines, is inserted through the top of the casing-body when the cover is open. In inserting the same, it is tilted forward and downward so 40 that the keyboard extension 17 thereof may be passed through an opening 18 in the front wall of the casing-body. It is then let down until its front and rear feet 19, 20 rest upon the base-piece 14, with the rear feet 20 in 45 locators 21 which are secured to the rear wall of the casing-body, and with the front feet 19 in suitable locators, not shown.

In order that there may be room for movement of the carriage 22 of the machine with 50 the platen 23 in letter-feed and return directions, the casing is expanded laterally outward and upward, as indicated at 24 in Figure 2; and, in order that the line-space lever 25, the carriage-return arm, not shown, 55 and the carriage-release lever, not shown, which are mounted on the carriage, may have movement with the carriage and yet be operable from without the casing, the casing has, at the front thereof, a slot 26 which 60 extends longitudinally thereof and which is formed by the lower front edge 27 of the cover and the upper edge 28 of the front wall of the casing-body. This slot is, however, 65 closed, except where the levers extend therethrough, by means of a cushion 29, secured

by screws 30 to the edge 27 of the cover, and by a cushion 31, secured by screws 32 to the edge 28 of the casing-body. The cushions 29 and 31 are sufficiently yieldable to permit of movement therealong of the operating 70 levers with the carriage. The screws 32 may also serve to secure the front lining member or members 13 to the casing-body.

Below the keyboard extension, the front wall of the casing-body comprises a cross-member 33. The comb-plate 34 of the typewriting machine is shown at Figure 2 above the casing cross-piece 33; and key-levers 35 are shown extending through the comb-plate of the machine. Above the comb-plate is 80 the front plate 36 of the machine, secured to the front corner-posts 37 of the machine-frame by screws 38. In front-strike machines, such, for instance, as the Underwood, the front plate ordinarily has an arcuate cut 39 therein for access to the types 40 for cleaning of the latter. For sound-deadening purposes, however, this cut 39 is closed by a correspondingly shaped plate 41, which, when in place, forms part of the front wall 90 of the machine. Heretofore, this plate has been removable from the interior of the casing when the casing-cover is open, to permit of access to the types for cleaning. In accordance with the present invention, the plate 41 is curled at 42 at its upper edge, and in the curl 42 is set a rod 43, the ends of which are pivoted at 44 in the segmental platform 45 of the front plate 36 of the machine. When access to the types is desired, the plate 41 is swung outward on its pivots 44, by means of a finger-piece 46. The upper edges of the plates 36 and 41 rest against a strip 48 of the front lining-member; and the casing is therefore closed to the emission 100 of sound at this point. The lining-member 48 being of yieldable material, such, for instance, as felt, no obstruction is offered thereby to the forward swing of the plate 41 on its hinges.

In order that the plate or door 41 may itself be sound-proof, it is lined in the following manner. On the plate 41 are shown five bosses 49 which are blind and which are threaded to receive screws 50, which hold thereto a plate 51 of the same shape as the plate 41; the plate 51 being set against the bosses 49, and a sheet of sound-deadening material 52 being set between the plates 41 and 51. The sheet 52 of sound-deadening material rests at its upper edge against the bead 42 of the plate 41, and at its lower edge projects slightly beyond the lower edge of the plate 41. The plate 41 is sufficiently 115 smaller than the cut 39 in the front plate 36 to permit of such projection of the lining-member 52. When, however, the plate or door 41 is in closed position, the lining-member 52 closes the crack between the plates 41 and 36, to seal the same against emission of 120 125 130

sound. The overlapping edge of the sound-deadening material 52 is slightly wider than the crack between the plates 41 and 36, but, the sound-deadening material being a yieldable material, such, for instance, as felt, the door 41 may, nevertheless, be closed. When it is closed, this overlapping edge of the material 52, by being jammed between the two plates, holds the door closed against accidental displacement.

For opening the casing, there is an arm 53 hinged to an ear 54 on the rear wall of the cover. The arm 53 is pivoted at 55 to the rear arm of a lever 56. The lever 56 is pivoted on a pin 57, which is secured to the side wall of the casing-body and which projects through the lining, not shown, on the side wall of the casing-body. The forward arm 58 of the lever 56 is offset at 59 to provide an ear which carries a forwardly-projecting pin 60. Loosely pivoted to the ear 59 by means of the pin 60, and held thereon by the head 61 of the pin, is a link 62 which is pivotally connected at its other end at 63 to an arm 64, fast on a rock-shaft 65. The rock-shaft 65 passes through the front wall of the casing and has a handle-piece 66 secured by a set-screw 67 to its outer or forward end. To provide an extended bearing for the rock-shaft 65, a collar or sleeve 68 thereon bears against the outer side of the casing front wall, and is held against displacement, longitudinally of the shaft, by means of another collar 69 secured by a set-screw 70 to the shaft. The shaft is free to turn in the sleeve 68. The collar 69 holds the shaft against rearward longitudinal displacement; and the hub 71 of the arm 64 on the shaft 65, by bearing against the inside of the front plate of the casing, holds the shaft 65 against forward longitudinal displacement. The lining-member 13 of the casing front wall is perforated to receive the hub 71 of the arm 64, and may be slotted to receive the link 62. When the palm of the operator's hand is pressed upon the handle 66 so as to turn the handle in counter-clockwise direction, the link 62 is thrust upward, and, by reason of its loose connection with the pin 60, causes the lever 56 to be rocked in counter-clockwise direction (as viewed in Figure 1) around its pivot 57, thereby causing the arm 53 to be rocked down and pressed rearward. The rearward pressure of the arm 53 causes the cover to swing open on its hinge 12. The movement of the handle 66 in the opposite direction causes the cover to be closed; or the cover may be closed by gravity, the opening connections being free to move therewith. The cover may also be opened by means of the usual handle 72 fast to the center front part of the cover.

The line-space lever 25 is a bell-crank lever pivoted at 73 to an ear 74 on the

carriage-frame. The longer forwardly-extending arm of the lever 25 is bent downward at 75, then offset forward at 76 between the cushions 29 and 31, to the outside of the casing where it carries a finger-piece 77 for operating the same. A shorter arm 78 of the line-space lever operates the line-space mechanism usually found in Underwood machines, and which comprises a slide 79 having forward and backward movement 75 on the carriage-frame. The slide 79 carries a pawl 80 for operating the ratchet-wheel 81 fast to the platen-shaft 82. Movement of the line-space lever to the right forces back the slide 79 and causes the pawl 80 to turn the ratchet-wheel. The slide 79 is returned to normal position by a spring, not shown.

The line-space lever has movement between two blocks 83 and 84 on the front rail 85 of the carriage. A cap-plate or guard 86 extends over the lever 25 and is secured to the blocks 83 and 84 by screws 87 and 88. For returning the line-space lever to normal position after each operation thereof, there is a coil spring 89 secured at one end at 90 to a pin on the arm 78 of the lever, and at its other end to a pin 91 on an ear 92 on the cap-plate 86. The ends of the spring 89 loosely engage the pins 90 and 91 so that the spring, as a whole, may have a pivotal movement on the pins when the lever is operated. This pivotal movement avoids bending of the spring where it is connected to the pins. It will be noted that, since the spring is connected at one end to the right-hand extremity of the lever, and at its other end connects to the left-hand extremity of the rail 85, the spring has considerable length. By reason of this length, and by reason of the elimination of bending of the spring at the pins 90 and 91, the strains thereon, incidental to the operation of the line-space lever, in movement of the same against the friction caused by the cushions, and which have heretofore resulted in breakage of the spring, are here taken care of, and a spring is provided which is not only durable but which may have the strength requisite to prompt operation of the lever against the friction of the cushions.

Variations may be resorted to within the scope of the invention, and portions of the improvements may be used without others.

Having thus described my invention, I claim:

1. The combination with a sound-deadening casing for a front-strike typewriting machine having a platen, type-bars pivoted to swing upward and rearward to the platen, and arranged to form a segmental type-basket, a front plate having a segmental opening therein in conformity with and for access to the type-basket for cleaning of the

- types, and a frame to which said front plate is so secured as to have a close fit with the front wall of the casing at each side of the keyboard opening in the latter; of a segmental plate for normally closing said segmental opening, the segmental plate being pivoted to the front plate to serve as a door which may be swung open at will.
2. The combination with a sound-deadening casing for a front-strike typewriting machine having a platen, type-bars pivoted to swing upward and rearward to the platen, and arranged to form a segmental type-basket, a front plate having a segmental opening therein in conformity with and for access to the type-basket for cleaning of the types, and a frame to which said front plate is so secured as to have a close fit with the front wall of the casing at each side of the keyboard opening in the latter; of a segmental plate for normally closing said segmental opening, the segmental plate being pivoted to the front plate to serve as a door which may be swung open at will, and being provided with a sound-deadening lining.
3. The combination with a sound-deadening casing for a front-strike typewriting machine having a platen, type-bars pivoted to swing upward and rearward to the platen, and arranged to form a segmental type-basket, a front plate having a segmental opening therein in conformity with and for access to the type-basket for cleaning of the types, and a frame to which said front plate is so secured as to have a close fit with the front wall of the casing at each side of the keyboard opening in the latter; of a segmental plate for normally closing said segmental opening, the segmental plate being pivoted to the front plate to serve as a door which may be swung open at will, and being provided with a sound-deadening lining which projects slightly beyond the edge of the segmental plate to seal the joint between the two plates.
4. The combination with a sound-deadening casing for a front-strike typewriting machine having a platen, type-bars pivoted to swing upward and rearward to the platen, and arranged to form a segmental type-basket, a front plate having a segmental opening therein in conformity with and for access to the type-basket for cleaning of the types, and a frame to which said front plate is so secured as to have a close fit with the front wall of the casing at each side of the keyboard opening in the latter; of a segmental plate for normally closing said segmental opening, the segmental plate being pivoted to the front plate to serve as a door which may be swung open at will, and being provided with a sound-deadening lining which is of soft flexible material, such, for instance, as felt, and which projects slightly beyond the edge of the segmental plate to be jammed in the joint between the two plates and thereby to serve to prevent accidental opening of the door.
5. The combination with a sound-deadening casing for a front-strike typewriting machine having a platen, type-bars pivoted to swing upward and rearward to the platen, and arranged to form a segmental type-basket, a front plate having a segmental opening therein in conformity with and for access to the type-basket for cleaning of the types, and a frame to which said front plate is so secured as to have a close fit with the front wall of the casing at each side of the keyboard opening in the latter; of a segmental plate for normally closing said segmental opening, the segmental plate being hinged to the front plate at the upper edges of the two plates and having a handle on the front thereof whereby the segmental plate may be swung open at will.
6. The combination with a sound-deadening casing for a front-strike typewriting machine having a platen, type-bars pivoted to swing upward and rearward to the platen, and arranged to form a segmental type-basket, a front plate having a segmental opening therein in conformity with and for access to the type-basket for cleaning of the types, and a frame to which said front plate is so secured as to have a close fit with the front wall of the casing at each side of the keyboard opening in the latter; of a segmental plate for normally closing said segmental opening, the upper edge of the segmental plate being curled and having hinge pins in the curl for pivotally connecting the same to the front plate, whereby the segmental plate may be opened at will.
7. The combination with a sound-deadening casing for a typewriting machine having a platen, type-bars pivoted to swing to the platen, a front plate for the machine having an opening therein for access to the types for cleaning thereof, and a frame to which said front plate is so secured as to have a close fit with the front wall of the casing at each side of the keyboard opening in the latter; of a door for the opening in said front plate, comprising two plates with a sheet of sound-deadening material between the same.
8. The combination with a sound-deadening casing for a typewriting machine having a platen, type-bars pivoted to swing to the platen, a front plate for the machine having an opening therein for access to the types for cleaning thereof, and a frame to which said front plate is so secured as to have a close fit with the front wall of the casing at each side of the keyboard opening in the latter; of a door for the opening in said front plate, comprising two plates with a sheet of sound-deadening material

between the same, one of the door plates having threaded bosses thereon, and screws passing through the other door plate into the bosses to hold the plates and lining material together.

9. The combination with a sound-deadening casing for a typewriting machine having a platen, type-bars pivoted to swing to the platen, a front plate for the machine having an opening therein for access to the types for cleaning thereof, and a frame to which said front plate is so secured as to have a close fit with the front wall of the casing at each side of the keyboard opening in the latter; of a door for the opening in said front plate, comprising two plates with a sheet of sound-deadening material between the same, one of the plates having bosses thereon against which the other of the door plates is set, and means for holding the plates together.

10. The combination with a sound-deadening casing for a front-strike typewriting machine having a platen, type-bars pivoted to swing upward and rearward to the platen, and arranged to form a segmental type-basket, a front plate having a segmental opening therein in conformity with and for access to the type-basket for cleaning of the types, and a frame to which said front plate is so secured as to have a close fit with the front wall of the casing at each side of the keyboard opening in the latter; of a segmental plate for normally closing said segmental opening, the segmental plate being pivoted to the front plate to serve as a door which may be swung open at will; the sound-deadening casing containing the typewriting machine and having an opening in the front wall thereof, through which the keyboard extension of the machine projects, and which is closed above the keyboard extension of the machine by the front plate of the machine, and by the door in the latter, when the machine is in place.

11. The combination with a sound-deadening casing for a front-strike typewriting machine having a platen, type-bars pivoted to swing upward and rearward to the platen, and arranged to form a segmental type-basket, a front plate having a segmental opening therein in conformity with and for access to the type-basket for cleaning of the types, and a frame to which said front plate is so secured as to have a close fit with the front wall of the casing at each side of the keyboard opening in the latter; of a segmental plate for normally closing said segmental opening, the segmental plate being pivoted to the front plate to serve as a door which may be swung open at will; the sound-deadening casing containing the typewriting machine and having an opening in the front wall thereof, through which the keyboard extension of the machine

projects, and which is closed above the keyboard extension of the machine by the front plate of the machine and by the door in the latter, when the machine is in place; and a strip of flexible lining material, such, for instance, as felt, serving as a closure for the joint between the casing and the top of the front plate of the machine, and which is yieldable to permit opening of the door.

12. The combination with a sound-deadening casing, and a typewriter within the casing having its keyboard projecting beyond the casing for operation, of a cover for the casing hinged at the rear to swing upwardly, a rock-arm mounted to swing at one side of the keyboard in close proximity thereto for actuation by the operator, and mechanism directly connecting said rock-arm with said hinged cover, whereby swinging down on the arm will cause direct upward swing of the cover.

13. The combination with a sound-deadening casing, and a typewriter within the casing having its keyboard projecting beyond the casing for operation, of a cover for the casing hinged at the rear to swing upwardly, a rock-arm mounted to swing at one side of the keyboard in close proximity thereto for actuation by the operator, and mechanism directly connecting said rock-arm with said hinged cover, whereby swinging down on the arm will cause direct upward swing of the cover, said connecting mechanism including toggle-links pivoted one on the cover and the other on the machine-frame whereby swinging the latter link by said rock-arm will raise the cover and hold it in raised position.

14. The combination with a sound-deadening casing, and a typewriter within the casing having its keyboard projecting beyond the casing for operation, of a cover for the casing hinged at the rear to swing upwardly, a rock-arm mounted to swing at one side of the keyboard in close proximity thereto for actuation by the operator, and mechanism directly connecting said rock-arm with said hinged cover, whereby swinging down on the arm will cause direct upward swing of the cover, said mechanism including toggle-links that will raise the cover and maintain it in raised position, which mechanism on swinging said arm in opposite direction will break the toggle-links and directly cause return of the cover to closed position.

15. The combination with a sound-deadening casing, and a typewriter within the casing having its keyboard projecting beyond the casing for operation, of a cover for the casing hinged at the rear to swing upwardly, a rock-shaft extending through the casing, an arm on the rock-shaft at one side of the keyboard in proximity thereto for rocking said shaft by the operator with the hands in writing position, and actuating means

- directly connecting said shaft inside of the casing with the cover to cause swinging of such shaft by the operator to swing the cover upwardly.
16. The combination with a sound-deadening casing, and a typewriter within the casing having its keyboard projecting beyond the casing for operation, of a cover for the casing hinged at the rear to swing upwardly, a rock-shaft extending through the casing, an arm on the rock-shaft at one side of the keyboard in proximity thereto for rocking said shaft by the operator with the hands in writing position, and actuating means directly connecting said shaft inside of the casing with the cover to cause swinging of such shaft by the operator to swing the cover upwardly, said shaft having another arm-portion arranged whereby depression of the same will directly swing the cover back to closed position.
17. The combination with a sound-deadening casing, and a typewriter within the casing having its keyboard projecting beyond the casing for operation, of a cover for the casing hinged at the rear to swing upwardly, a rock-shaft extending through the casing, an arm on the rock-shaft at one side of the keyboard in proximity thereto for rocking said shaft by the operator with the hands in writing position, and actuating means directly connecting said shaft inside of the casing with the cover to cause swinging of such shaft by the operator to swing the cover upwardly, and which arm will close the open cover when swung in the opposite direction.

ALFRED G. F. KUROWSKI.
